UNITED STATES PATENT OFFICE

KARL FRIEDRICH WAGNER, OF STUTTGART, GERMANY, ASSIGNOR, BY MESNE ASSIGNMENTS, TO MAGNESIUM DEVELOPMENT CORPORATION, OF NEWARK, NEW JERSEY, A CORPORATION OF DELAWARE

AUTOMATIC DIE-CASTING APPARATUS

Application filed August 31, 1931, Serial No. 560,430, and in Germany September 15, 1930.

This invention relates to improvements in and relating to automatic die-casting apparatus and more particularly to a device for preventing the injection pressure in such apparatus from continuing in the pressure chamber during breakdowns.

In the case of automatic die-casting machines, especially such as are hydraulically controlled, in which the majority of the working operations are performed or initiated, in definite succession and at definite intervals—for example by means of one or more camshafts, such as disclosed in United States Letters Patent 1,724,332 to Will et al., issued Aug. 13, 1929—it has been found necessary to adopt measures which, in the event of any sudden stoppage of the machine—especially failure of the energy required for actuating the control devices—at a time when the injection pressure is acting upon the metal in the pressure chamber, will prevent the protracted continuance of said pressure in the chamber, since, under such conditions, the walls of the chamber would be subjected to undue stress.

The present invention aims at enabling the pressure chamber to be relieved automatically, that is to say, independently of the control or actuating mechanism of the machine, in case of emergency.

To this end, according to the invention, a valve is provided in the pipe leading to the pressure chamber or is located in that portion of the pressure chamber which is not occupied by metal, and said valve is retained in the working position by the forces actuating the machine or the control mechanism, but is adapted, in the event of failure of the actuating forces, to move into a position establishing free communication between the pressure chamber and the atmosphere, and at the same time shutting off the injection-pressure pipe.

In order to more clearly understand the invention, reference is made to the accompanying drawing, which illustrates diagrammatically and by way of example, one embodiment thereof.

In said drawing, a slide valve *b* moving in a casing *a* is retained in a position while

the machine or control is in operation, in which it maintains free communication between the injection-pressure pipe and the pressure chamber. In the embodiment shown, the valve is retained in the corresponding position by an electromagnet *c*, which is energized by the current driving the camshaft motor.

If this current fails, from any cause, the slide valve will descend in the casing *a* under the influence of a weight *f* attached to the slide *b* for a distance determined by the stop *d*. In this position, the valve places the pressure chamber in communication with the atmosphere, by way of the passage *e*, so that the pressure in the chamber is promptly relieved, and, on the other hand, the injection-pressure pipe is shut off.

I claim:

1. A safety device in pressure die-casting machines comprising a valve in the pressure supply pipe leading to the pressure chamber, means for retaining said valve in working position, actuated by the forces operating the machine, and means for automatically shifting said valve into a position adapted to bring about free communication between the interior of the pressure chamber and the atmosphere, when such operating forces cease to act.

2. A safety device in pressure die-casting machines comprising a valve in the pressure supply pipe leading to the pressure chamber, means for retaining said valve in working position actuated by the forces operating the machine, and means for automatically shifting said valve into a position adapted to shut off the pressure supply and to bring about free communication between the interior of the pressure chamber and the atmosphere, when such operating forces cease to act.

3. A safety device in pressure die-casting machines comprising a valve casing inserted in the pressure supply pipe leading to the pressure chamber, a slide movably fitted in said casing, a bore in said slide adapted to establish free connection between the pressure supply and the pressure chamber when said slide is in one extreme position, and another bore adapted to establish free connection be-

tween the pressure chamber and the atmosphere when said slide is in the opposite extreme position, an electromagnet core operating said slide and actuated by the current 5 operating the pressure die-casting machine, and means for limiting the movement of said slide in the direction away from said electromagnet core.

4. A safety device in pressure die-casting 10 machines comprising a valve in the pressure supply pipe leading to the pressure chamber, means for retaining said valve in working position whereby pressure is admitted to the pressure chamber, said valve retaining means 15 being actuated by the forces operating the machine, and means for automatically shifting said valve into position to shut off the pressure to the interior of said pressure chamber when the machine operating forces cease 20 to act.

In testimony whereof I have hereunto set my hand.

KARL FRIEDRICH WAGNER.
